UNITED STATES PATENT OFFICE.

RICHARD M. VAN VALKENBURGH, OF KANSAS CITY, MISSOURI, ASSIGNOR TO IRVING-PITT MANUFACTURING COMPANY, OF KANSAS CITY, MISSOURI, A CORPORATION OF MISSOURI.

LOOSE-LEAF BINDER.

Application filed August 1, 1925. Serial No. 47,399.

This invention relates to loose-leaf binders and particularly to that type of binder having a plurality of rings for receiving loose sheets, and the primary object of this invention is to provide effective means for opening the hooks comprising the sheet carrying rings.

Heretofore, it has been customary to attach the hook opening device to some member of the loose-leaf binder other than the hook-carrying members upon which it acts. It is the object of this invention to provide a novel structure for opening the hooks which is supported by the hook-carrying members and which does not depend upon any other element of the structure for its effectiveness.

Another object of the present invention is the provision of a hook-opening member which is supported in such a way that the spring plate used to hold the hook-carrying members in the extreme open or closed position will be caused to relax its exerted force simultaneously with the upward thrust at a point on the line of meeting of said hook-carrying members.

It is a further object of this invention to provide a novel and neat construction to embody this invention, one that is easy and cheap to make and not likely to get out of order after it has been assembled at the factory.

An even further object of the instant invention is to provide a hook-opening member which is made a part of the binder structure in such a way that it is permanently locked in place after the binder is assembled and cannot be removed or will not accidentally be dislodged through rough usage.

Minor objects of the invention will appear during the course of the detailed specification which refers to the preferred way of making the hook-opening device as shown in the accompanying drawing, in which,

Figure 1 is a perspective view of the well known loose-leaf binder of the ring type showing the invention made a part thereof.

Fig. 2 is an enlarged vertical central section of the binder showing the hook-opening members, which are made in accordance with this invention, disposed at each end of the hook-carrying members.

Fig. 3 is an enlarged, fragmentary, detailed, cross section of the binder with the

hook-carrying members in the closed position, taken on line III—III of Fig. 2, looking in the direction of the arrow.

Fig. 4 is a similar detailed view with the hook-carrying members in the open or sheet-releasing position.

Fig. 5 is a fragmentary plan view of one end of the binder member showing the hook-opening member in place, and,

Fig. 6 is a perspective view of the hook-opening member constructed in accordance with this invention and removed from the binder.

Like reference characters refer to similar parts through-out the several views, and the numeral 7 designates an ordinary loose-leaf binder of the ring type having the well-known spring plate 8 which is adapted to engage the two hook-carrying members 9 along their outer edges to maintain the same in either the open or closed position. When it is desired to remove or add sheets 10 from or to the well known hooks 11, carried by the members 9, the hook-carrying members 9 assume the position shown in Fig. 4.

In moving the members 9 from the closed position to the open, or from the position shown in Fig. 3 to that illustrated in Fig. 4, spring plate 8 must be flexed so that the engaging edges thereof are forced outwardly.

It is known in the art that many devices for operating the hook-carrying members 9 to open hooks 11 have been designed. Previously, the hook-opening member, having a portion thereof in engagement with the hook-carrying members 9, was supported by some member of the binder other than directly by the two hook carrying members at a point where its operation did not tend to exert the proper pressure at the edges of spring plate 8.

This invention contemplates a hook-opening member which may be constructed substantially as shown in Fig. 6 of the drawing, and which has a pair of fulcrums 12, the upwardly extending stem 13 of which passes through openings 14 formed near the outer edges, close to the meeting edges of member 9 and spring plate 8, and adjacent each end of the hook-carrying members 9. Fulcrums 12 bear upon the upper surface of each of the hook-carrying members 9 and hold the hook-opening member away from and out of engagement with any other member of the

binder. One of these hook-opening members should be provided at each end of the binder as shown in Fig. 2, and may have a suitable portion such as the dome 15 to engage hook-carrying members on their under sides at a point where the same meet on a line intermediate fulcrum points 12. This dome 15 is slightly behind fulcrums 12, and finger engaging member 16 is disposed on the opposite side of fulcrum points 12 in order that an upward pressure to dome 15 may be given when a downward pressure is exerted on finger member 16. When this pressure is exerted, it is obvious that the force will flex spring plate 8 slightly, which will permit hook-carrying members 9 to be more easily sprung to the open position as shown in Fig. 4, thus carrying the hook members 11 to the open position.

It is plain that the downward pull exerted on the outer edges of hook-carrying members 9 by fulcrums 12 when pressure is brought to bear upon finger member 16, will aid in stabilizing member 9 as the upward pressure is exerted along the meeting line thereof by dome 15 and will act upon plate 8 as if the fulcrum points were attached directly thereto.

It has been found that this structure will open the ordinary ring binder with much less pressure than the openers now commonly used. The fact that the binder may be assembled with the opener in position, i. e. supported by members 9 is also an advantage since the addition of parts other than the actual hook-opening member itself is not required. Also, the hook-opening member cannot be removed without disassembling the binder.

It is understood that many changes in the construction of this invention may be made without departing from the spirit thereof and it is desired to be limited only by the scope of the appended claims.

What is claimed is:

1. In combination with a loose-leaf binder having a pair of rockingly mounted hook-carrying members and a spring plate, means for opening said hook-carrying members including means for reducing the force exerted by said spring plate upon said hook-carrying members as the hook-carrying members are being urged to the open position, said opening means comprising a lever fulcrumed on said members adjacent said spring plate and adapted to be assembled with said members as a unit.

2. In combination with a loose-leaf binder having a pair of rockingly mounted hook-carrying members, means supported solely by said hook-carrying members adjacent their oppositely disposed edges for opening the hooks carried thereby and adapted to be assembled with said members as a unit.

3. In combination with a loose-leaf binder

having a pair of rockingly mounted hook-carrying members, means supported by said hook-carrying members adjacent the ends thereof adapted to open the hooks carried thereby, said hook-opening means being supported free of the remaining parts of said binder and adapted to be assembled with said members as a unit.

4. In combination with a loose-leaf binder having a pair of rockingly mounted hook-carrying members held by a spring plate, means supported by said hook-carrying members adjacent the edges engaged by said spring plate adapted to open the hooks carried thereby, said means and members being assembled as a unit in said binder.

5. In a loose-leaf binder a pair of rockingly mounted hook-carrying members having openings adjacent their outer edges and ends, means adapted to open the hooks having members passing through said openings to engage said hook-carrying members on the upper surface thereof whereby said hook opening means is supported solely by said members.

6. In a loose-leaf binder a pair of rockingly mounted hook-carrying members each having an opening adjacent the outer edge at each end thereof and means for rocking said members to the open position having fulcrums extending upwardly through each of said openings respectively to engage the upper surface of each hook-carrying member.

7. In a loose-leaf binder a pair of rockingly mounted hook-carrying members, means carried by said members having a plurality of fulcrums adapted to engage each hook-carrying member and means for engaging said members at their meeting edges to open the hook when said member is rocked on said fulcrums.

8. In a loose-leaf binder a pair of rockingly mounted hook-carrying members, means carried by said members having a pair of fulcrums and an engaging member adapted to engage said hook-carrying members at their meeting edges and on a line intermediate said fulcrums.

9. In a loose leaf binder, the combination of a pair of toggle plates articulated at their inner ends, a base plate including means for exerting a yielding pressure on the remote edges of the toggle plates, and means comprising a lever fulcrumed on said plates adjacent said remote edges for simultaneously pressing upwardly on the toggle plates and relieving the pressure on the remote edges thereof, said lever and members being assembled as a unit in said binder.

10. In a loose leaf binder, the combination of pairs of paper holding prongs, a pair of toggle plates articulated at their adjacent edges to form a toggle adapted to bend upwardly to separate the pairs of prongs and to bend downwardly to bring the prongs

together, a channeled resilient base plate receiving the toggle plates and exerting a yielding pressure on their remote edges, and a lever fulcrumed on said plates adjacent said remote edges adapted to simultaneously press upwardly on the intermediate portion of the toggle and downwardly on the side of

the portions of the base plate, said lever and members being assembled as a unit in said binder. 10

In testimony whereof I hereunto affix my signature this 29th day of July, 1925.

RICHARD M. VAN VALKENBURGH.
